UNITED STATES PATENT OFFICE.

HENRY ALTSCHUL, OF NEW YORK, N. Y.

HOLDER FOR POLISH OR OTHER SUBSTANCES.

SPECIFICATION forming part of Letters Patent No. 718,969, dated January 27, 1903.

Application filed March 3, 1902. Serial No. 96,410. (No model.)

To all whom it may concern:

Be it known that I, HENRY ALTSCHUL, a citizen of the United States, residing at the city of New York, borough of Manhattan, in the county and State of New York, have invented certain new and useful Improvements in Holders for Polish or other Substances, of which the following is a full, clear, and exact specification.

10 My invention relates to improvements in receptacles for packing shoe-polishes, soap, and other substances; and said invention has for its object, more particularly, to provide a receptacle for the purposes above named 15 wherein the contents may be kept fresh and ready for use and by means of which receptacle the contents may be readily extracted in such quantities as may be desired without soiling the hands and without unnecessarily exposing the contents of the receptacle to the atmosphere. These objects above set forth 20 I am enabled to attain by means of my invention, which consists in the novel details of construction and in the combination, connection, and arrangement of parts hereinafter described and then pointed out in the claims.

In the accompanying drawings, forming part of this specification, wherein like letters of reference indicate like parts, Figure 1 shows 30 a perspective view of a holder with cap detached made in accordance with and embodying my invention. Fig. 2 is a central section of the same, showing the cap in position thereon; and Fig. 3 is a perspective view of the upper portion of a holder, also with cap detached, illustrating a modified construction.

In said drawings, A designates a holder comprising a cylindrical box B, open at its upper and lower ends and provided with an inwardly-projecting flange a at its base and an annular rib b upon the surface of said box B near its top. Within the box B is arranged a follower C, having depending sections C' 40 arranged closely together along its edge, which sections are adapted to contact with the inner wall of the box B and by means of the spring-pressure exerted thereby hold the follower C to its adjusted position within the 45 box B. Upon the top of the box B is disposed a perforated covering D, consisting of fabric or wire-gauze, depending upon the nature of

the contents of the box B and the purposes for which the same are to be used. The edges of the perforated covering D extend downwardly over the outer surface of the box B and the rib b thereon, and the same are secured in position upon said box B by means of an annular band E, having a rib c therein at about its middle which is adapted to fit 60 over the rib b on the box B and securely clamp the edges of the perforated covering D intermediate the same. The perforated covering D is preferably somewhat loosely disposed upon the top of the box B in order 65 to cause the same to assume substantially the shape indicated at Fig. 2 when the contents of the box are forced upward by the pressure exerted upon the follower C.

G denotes a cap adapted to be fitted upon 70 the box B over the annular band E, whereby to inclose and protect the perforated covering D and the contents of the box below said perforated covering.

In the modified construction illustrated at 75 Fig. 3 the upper portion of the box B' is provided at its opposite sides above the rib b' with teats (not seen) and the annular band E' provided at its opposite edges below the rib c' with recesses d, which are adapted to 80 engage the teats on the box B, and thereby lock the annular band E' in position upon the box B' and at the same time firmly secure the edges of the perforated covering D' intermediate said box and band. G' denotes a cap 85 for inclosing the upper part of the box B'.

The contents of the receptacle B are expressed therefrom by forcing the follower C upward, and thereby causing the contents to be forced outward in small quantities between the interstices of the perforated covering D, and thus enabling the user to apply the contents to the objects upon which the same are to be used without soiling the hands.

Should it become necessary in the course 95 of time by reason of continued use or for sanitary or other reasons, depending, of course, upon the nature of the contents of the holder, to substitute a new perforated covering, it simply becomes necessary to remove the band 100 E, remove the perforated covering, and then place a new perforated covering in position upon the top of the box and then slip the annular band E over the same upon the box.

Without limiting myself to the details of construction, which may be varied within the scope of the invention, what I claim, and desire to secure by Letters Patent of the United States, is—

1. A holder for the purposes specified comprising a receptacle open at its top and bottom, an annular rib arranged in said receptacle adjacent to its top, a follower arranged within said receptacle, a flexible, perforated covering disposed over the top of said receptacle, a removable band arranged upon said receptacle adjacent to its top adapted to inclose the edges of the perforated covering and hold the same in position upon said receptacle, substantially as specified.
2. A holder for the purposes specified comprising a receptacle open at its top and bottom, an annular rib arranged in said receptacle adjacent to its top, an inwardly-projecting

flange at its bottom, a follower arranged within said receptacle having depending sections adapted to contact with the interior wall of the receptacle, a gauze covering disposed over the top of said receptacle, an annular band upon said receptacle above the annular rib thereon adapted to inclose the edges of said gauze covering to hold said gauze covering in position upon said receptacle, a locking device for securing said annular band upon said receptacle, and a cap adapted to be fitted upon said band to seal the top of the receptacle, substantially as specified.

Signed at the city of New York, in the county and State of New York, this 26th day of February, 1902.

HENRY ALTSCHUL.
